UNITED STATES PATENT OFFICE.

JOHN CARROLL, OF OSWEGO, NEW YORK, ASSIGNOR TO GEO. B. SLOAN, JR.,
OF OSWEGO, NEW YORK.

END PLATE FOR SPRINGS.

SPECIFICATION forming part of Letters Patent No. 718,090, dated January 13, 1903.

Application filed December 13, 1901. Serial No. 85,754. (No model.)

To all whom it may concern:

Be it known that I, JOHN CARROLL, of Oswego, in the county of Oswego, in the State of New York, have invented new and useful Improvements in End Plates for Springs, of which the following, taken in connection with the accompanying drawings, is a full, clear, and exact description.

My invention relates to the bearing-plates fitted to the ends of leaf-springs on which the load is supported; and it consists in a particular construction of such end plate by which it is firmly yet detachably secured to the end of the leaf by mechanical means without injuring or weakening the parts.

Heretofore such bearing-plates have commonly been secured to the end of the main leaf of the spring by hot or cold welding, so that the plate was permanently secured in position without possibility of removal, and when heat was applied there was danger of injuring or weakening the parts, of burning the main-leaf spring, or drawing the temper, rendering it brittle. I have overcome such defects by forming the main leaf with a curved end and the bearing-plate with lugs engaging with this curved end, so that when the plate is adjusted in position it is locked securely against the possibility of accidental removal and yet can be easily removed, renewed, and replaced by hand without the use of any tool and without bending or breaking any of the parts.

My invention will be understood by reference to the drawings, in which the reference-numerals of the specification indicate the same parts in all the figures.

Figure I is a side elevation of a semi-elliptic spring having the bearing-plate in position on one end. Figs. II and III are respectively a side elevation and a bottom plan of the end of the main leaf enlarged. Figs. IV and V are respectively a side elevation and a bottom plan of a bearing-plate. Fig. VI shows the manner of adjusting the plate in position on the main leaf. Figs. VII and VIII are bottom plans of the end plate, showing modification in the form of the lugs.

In the figures, 1 indicates the semi-elliptic spring, of which the various leaves are locked together by band 2, 3 being the main leaf, having each end 4 curved or hooked to form

a rather shallow cross-groove 5 on its lower surface and with cut-out recesses 6 on the sides. This groove is preferably the arc of a circle, and the top 7 of the hook is formed in 55 the arc of a similar or smaller circle, whereby a strong hook on the end of the main leaf is produced to engage with the lugs on the bearing-plate and maintain it securely in one position.

10 is the end plate or bearing-plate, formed to fit the end of the main leaf, so that it may be easily swung or rocked into engagement, as illustrated in Fig. VI, where the end of the main leaf is shown in elevation and the plate 65 in section. The end plate is formed with end flange 11, covering or protecting the end of the main leaf or hook, with the side flanges 12 fitting the end recesses, so as to be flush with the edge of the main leaf and the whole 70 spring, and with the inwardly-extending lugs 13 integral with said side flanges and fitting the cross-groove 5. These lugs are preferably curved on their upper surfaces and flat on their lower, substantially to fit and fill said 75 grooves and lie flush with the under surface of the main leaf and extend inwardly, as best shown in Fig. V, about to the edge of the hanger-slot in the end plate, though they may be shorter, as shown in Fig. VII, or connected 80 and cut away by the slot, as shown in Fig. VIII. The plate may be variously formed to receive and support various forms of hangers, such as the well-known "stirrup" hanger, depending on each side of the end plate and 85 spring, or the "gib" hanger 20, as hereshown, depending through slot 21 in the end plate and slot 22 in the main leaf and sustained in groove 23 on top of end plate by pin 24, or may be formed in well-known way, with upper 90 ears and bolt to support upper element of spring.

My bearing-plate, made of wrought or malleable iron or other suitable material, is economical to make and to apply to the spring 95 and is not liable to be accidentally removed and lost and yet can be easily removed by hand when the weight is taken off the spring without the danger of injuring any of the parts by the use of a tool, so that neither the 100 end plate nor, what is more important, the spring is injured by the assembling or sepa-

rating of the parts. It is particularly adapted for use with heavy springs, such as elliptic or semi-elliptic, used for locomotives, tenders, &c., or may be applied to lighter springs and 5 those of various forms.

Having thus described my invention, what I claim, and desire to secure by Letters Patent, is—

1. The combination with a semi-elliptic 10 spring having curved ends, of end plates fitted to said ends and resting thereon, and an integral portion or portions of said plate extending under the curved ends to maintain the plate in position.
- 15 2. In a leaf-spring, the combination with the main leaf having a cross-groove on its under side near each end, of plates fitting said ends and having integral lugs fitting the groove, to maintain the plates securely in position against accidental displacement.
- 20 3. In a spring-leaf, the combination with a series of leaves, of a main leaf having curved or hooked ends and a cross-groove on the under side of each hook, of a plate fitted to 25 said ends, and integral lugs on the lower side of said plate fitting the groove and adapted to maintain the plate securely in position on the main leaf.
- 25 4. In an elliptic or semi-elliptic spring, the combination with a main leaf having a cross-groove on its under side near each end, of a bearing-plate fitting the ends of the spring, integral lugs on under side of the plate inwardly extending toward each other, formed 35 with their upper surfaces fitted to the groove and their lower surfaces flat to correspond with the lower surfaces of the spring, whereby the end plate is maintained securely in position on the spring.
- 40 5. In a semi-elliptic spring, the combination with a main leaf having hooked ends forming a cross-groove on their under sides, of bearing-plates fitted to said ends, integral flanges on the sides of the plates depending 45 on each side of the main leaf and integral, inwardly-extending lugs on said side flanges, said lugs being substantially fitted to the groove to lock the plate in position.
- 50 6. In a semi-elliptic spring, the combination of a main leaf having curved or hooked ends formed with a cross-groove on their under surfaces, of bearing-plates having integral end flanges depending at the end of the leaf, integral side flanges continuous with the 55 end flanges depending on the sides of the leaf and integral, inwardly-extending lugs on said

side flanges fitted to the grooves, to lock the plates in position.

7. In a semi-elliptic spring, the combination with a main leaf, of integral curved or hooked ends on said leaf having recesses on each side at the end and a cross-groove on their under side formed in the arc of a circle, the top of said hook being a ridge formed also in the arc of a circle, of bearing-plates fitted 65 to said hooked ends, integral end flanges on said plates covering the end of the main leaf, integral side flanges on the plates fitting said recesses and integral inwardly-extending lugs on said flanges fitted to the cross-groove and 70 adapted to lock the plate against accidental displacement.

8. In a leaf-spring, the combination with a main leaf having its ends formed with cross-grooves and recesses on each side at the end, 75 said groove being the arc of a circle and the end of the spring above the groove being a ridge in the arc of a smaller circle, bearing-plates fitted to said ends, integral flanges fitting the recesses and lying flush with the 80 sides of the leaf, and lugs on the flanges to fit and fill the grooves, where the parts are assembled.

9. In a semi-elliptic spring, the combination with the main leaf having curved or 85 hooked ends, of bearing-plates fitted to said ends, and extensions on the bearing-plates to engage with said ends and maintain the bearing-plates securely but detachably in position.

10. In a semi-elliptic spring, the combination with the main leaf having curved or bent ends, of bearing-plates fitted to said ends and resting thereon, and integral extensions on the bearing-plates to engage with said ends, when the bearing-plates are adjusted in position, and adapted to maintain the bearing-plates securely but detachably in position on the springs. 95

11. In a semi-elliptic spring, the combination with the main leaf, of bearing-plates arranged above and supported on said leaf at both ends, and integral lugs on said plates engaging with grooves on the under side of said leaf, whereby the plates are maintained securely but detachably in position. 105

In testimony whereof I have hereunto signed my name.

JOHN CARROLL. [L. s.]
